UNITED STATES PATENT OFFICE.

HIROSUKE HORIUCHI, OF TAIWAN, JAPAN.

VERTICAL CYLINDRICAL WATER-TUBE BOILER.

1,313,692.

Specification of Letters Patent.

Patented Aug. 19, 1919.

Application filed March 13, 1917. Serial No. 154,643.

To all whom it may concern:

Be it known that I, HIROSUKE HORIUCHI, a subject of the Empire of Japan, residing at 41 2-chome, Tomongai, Taihokujonai, 5 Taihokucho, Taiwan, Japan, have invented certain new and useful Improvements in Vertical Cylindrical Water-Tube Boilers, of which the following is a specification.

This invention relates to improvements 10 in vertical cylindrical water-tube boilers in which a boiler shell with a concave end-plate is mounted on a furnace shell, and a broad cylindrical combustion chamber being placed with a slight inclination in the 15 boiler shell, a number of vertical water-tubes are arranged with a slight inclination in the combustion chamber near the central point of the boiler shell, and the said combustion chamber, with a suitable space left 20 in its rear portion, opens by an inclined flue to the furnace, while the said chamber, with a smoke tube provided on its front face, opens to the front face of the boiler shell to communicate with a chimney, and 25 also a certain device is provided so constructed as the hot air generated between the circular wall of the furnace and the furnace shell ejects to the rear space of the combustion chamber to effect perfect combustion.

The objects of this invention are advantageously to arrange numerous water-tubes in a vertical boiler shell having a limited space, and to render the combustion of 35 fuel perfect and the conduction of heat effective, and also to promote the circulation of feed water, and further, to make it easy to inspect every part in the boiler, which has hitherto been very inconvenient to do.

40 In the accompanying drawings,

Figure 1 is a vertical sectional view of a boiler embodying my invention.

Fig 2 is an enlarged end view of the spray nozzle.

45 The lower part 2 of a cylindrical shell 1 is conical; its diameter is a little increased downward, and its concave end-plate 3 shaped as an inverted dish is removably mounted on a furnace shell 4 which, provided with a grate 5, forms a broad furnace.

50 The cylindrical combustion chamber 6 is placed with a slight inclination in the shell 1, and a number of water-tubes 7 are arranged with a slight inclination between the upper and lower plates of the combus-

tion chamber, with a suitable space left in its rear portion, and an inclined flue 8 is provided between the lower part of the said space and the central part of the end-plate 60 3, so that the upper portion of the furnace communicates with the combustion chamber, and a smoke tube 9 being provided at the front face of the combustion chamber opens to the front face of the shell, and a smoke 65 box 10 being provided on the said front face of the shell communicates with the chimney 11 direct, or through a side flue suitably formed around the periphery of the shell to utilize the waste heat communi- 70 cates with the chimney.

The combustion chamber 6 is preferably made as large in diameter as the circumstances permit, and an upper corner 6' of the rear part of the said chamber is rounded 75 to leave a space for the circulation of water, and is provided with a suitable number of gusset stays 12 on its external surface so as to suspend the combustion chamber in the shell. Some of the water-tubes 7, say, tubes 80 7' 7' are provided as stay tubes against the strain of the upper and lower plates of the combustion chamber.

Above the grate, a circular wall 13 is provided, and an annular space 14 is formed 85 between the outer circumference of the wall 13 and the inner circumference of the furnace shell 4, and a current of hot air generating in the annular space is conducted backward by means of a leading pipe 15. A 90 sustaining tube 16 is provided between the rear part of the combustion chamber and the boiler shell 1, and an injector 17 is inserted therein, said injector being connected with the said leading pipe 15 and a 95 dry steam pipe 18, the hot air is ejected to the combustion chamber, so that the flames ascending from the flue being supplied with the hot air, perfect combustion is brought about.

100 The nozzle 19 of the injector is shaped thinner and broader toward its front end, as shown in the drawing, and is made freely turnable by the provision of a handle 20, so when the combustion chamber and the 105 water-tubes are to be cleaned, the nozzle is turned, and as the turning goes on, the steam is ejected around the sustaining tube in a thin and consequently powerful current, passing in turn through all the spaces in 110 the combustion chamber, whereby the soot adhered to the surfaces of water-tubes shall

be effectively blown away. In common occasions, the broad surface of the nozzle is kept horizontally. In the drawing, the said surface of the nozzle is shown in the 5 vertical position for the sake of convenience.

In this vertical boiler, the flames produced by the combustion of fuel on the grate 5, first, heat the end-plate 3, and next, 10 entering into the combustion chamber 6 through the flue 8 from the central part of the end-plate, mix with the hot air ejecting from the injector 17, and effecting perfect combustion in the combustion chamber 65 conduct the heat into the water-tubes 7, and then 15 leaving the combustion chamber enter into the chimney 11 through the smoke tube 9.

The water heated at the bottom of the shell ascends along the central portion of 20 the shell mainly through the water-tubes 7, while the cold water descends along the circumference of the shell, thus the circulation of water is promoted. The steam produced 25 accumulates in the steam dome at the upper portion of the shell, while the mud, etc., accumulate in the concave space between the lower part 2 of the shell and the end-plate 3.

According to this invention, as above described, firstly, a broad combustion chamber 30 may be provided in a vertical boiler shell which is of a limited capacity, so that more water-tubes may be arranged, with the result that the heating surface is greatly increased; secondly, the water-tubes being 35 arranged near the center of the boiler shell with a slight inclination, the conduction of heat and the circulation of water are most effective; thirdly, the end-plate being made concave, the furnace may be enlarged in 40 capacity and the inspection of the bottom of the shell is rendered very easy; fourthly, the combustion of fuel is perfect. In short, the present invention avoiding all the defects in ordinary vertical boilers, the production of steam is most effective, and the 45 efficiency of boiler is greatly increased.

I claim:—

1. A vertical cylindrical water tube boiler, comprising a furnace shell, a boiler shell 50 having a concave end plate mounted on the furnace shell and removably supported and forming an annular space between the circular wall of the grate and the furnace shell, a broad cylindrical combustion chamber with- 55 in the boiler shell in a slightly inclined posi-

tion, a number of vertical water tubes slightly inclined and extending through the upper and lower plates of the combustion chamber and arranged to leave a suitable space in the rear portion thereof and open to the 60 central part of the end plate by an inclined flue, a smoke tube communicating with the front face of the combustion chamber and communicating with a chimney, a pipe leading from the annular space and ejecting hot 65 air into the rear space of the combustion chamber by an injector and said injector having a flat turnable nozzle normally held horizontal for supplying a thin and powerful current of hot air uniformly to the 70 flame ascending from the flue, and adapted to clean the water tubes when turned in a vertical position.

2. A water-tube boiler comprising a furnace shell, a combustion chamber within the 75 boiler shell, a number of vertical water tubes extending through the upper and lower plates of the combustion chamber and arranged to leave a suitable space in the rear portion thereof, a pipe leading through the 80 shell and into the rear space of the combustion chamber and ejecting hot air therein, said pipe having a flat turnable nozzle normally held horizontal for supplying a thin and powerful current of hot air uniformly to the 85 flame and adapted to clean the water tubes when turned in a vertical position.

3. A water tube boiler, comprising a furnace shell, a boiler shell having an annular 90 space adjacent the grate, a combustion chamber within the boiler shell, a number of vertical water tubes extending through the upper and lower plates of the combustion chamber and arranged to leave a space at 95 the rear, a pipe leading from the annular space and ejecting hot air into the rear space of the combustion chamber by an injector and said injector having a flat turnable nozzle normally held horizontal for supplying 100 a thin and powerful current of hot air uniformly to the flame ascending from the flue, and adapted to clean the water tubes when turned in a vertical position.

In testimony whereof I have affixed my 105 signature in presence of two witnesses,

HIROSUKE HORIUCHI.
